Application December 6, 1949, Serial No. 6,442
In Great Britain January 25, 1949

Term of patent 14 years

(Cl. D44—1)

To all whom it may concern:

Be it known that we, Eric Cecil Burns and Denis Osmond Burns, British subjects, residing at 1224 Yardley Wood Road, Warstock, Birmingham 14, county of Warwick, England, have invented a new, original, and ornamental Design for a Nutcracker, of which the following is a specification, reference being had to the accompanying drawing, forming part thereof, in which:

Figure 1 is a perspective view of a nutcracker embodying our new design;

Figure 2 is a further perspective view of the nutcracker shown in Figure 1;

Figure 3 is a view in side elevation of the nutcracker shown in Figures 1 and 2; and

Figure 4 is a plan view of the nutcracker shown in Figures 1, 2 and 3.

Figures 3 and 4 are shown to a larger scale than Figures 1 and 2.

We claim:

The ornamental design for a nutcracker, as shown.

ERIC CECIL BURNS.
DENIS OSMOND BURNS.
